UNITED STATES PATENT OFFICE.

LOUIS C. BONNOT, OF LOUISVILLE, OHIO, ASSIGNEE TO THE BONNOT COMPANY, OF CANTON, OHIO, A CORPORATION OF OHIO.

PULVERIZING MILL.

Application filed May 23, 1925. Serial No. 32,347.

The invention relates to a rotary drum grinding or pulverizing mill partly filled with balls, pebbles or the like; and the object of the improvement is to provide a machine which can be operated at low speed and will continuously deliver a predetermined unvarying powdered product, without any adjustments or changes in the machine and without the use of separating or grading apparatus.

The improved mill is well adapted for pulverizing small lump or slack coal for supplying powdered fuel directly into a furnace or a fuel feeding system, and the invention is illustrated and described with reference to such a use of the mill, without intending to limit it thereto.

In mills of this type an axial tube extending into and sometimes through the mill has been used for withdrawing the powdered product from the drum through one end of the tube; and such mills have been designed for and generally operated with such a quantity of grinding balls as will occupy considerably less than one-half the cavity of the drum.

Mills of this kind have sometimes been operated at such a speed and with such a frictional engagement of its peripheral wall, supplemented by the action of centrifugal force, that the grinding balls are carried upward on the rear side of the axial tube and thence forward over and above the same, so as to flow freely downward through space, either against the peripheral wall of the drum or upon the grinding balls in front of the tube.

For the purpose of increasing the grinding efficiency of such a mill, it has been proposed to provide a stationary deflecting wall extending from end to end directly upward from the rear side of the axial tube to the peripheral wall of the drum, to serve as a baffle or an abutment for the grinding balls and ground material moving upward in the rear side of the drum, to deflect the same from falling forward so as to shower downward upon the ascending body of balls and raw material in rear of the axial tube, for a direct grinding action therewith.

In the operation of both of such kinds of mills, however, the grinding balls return to the lower part of the drum by falling freely downward, more or less separated from each

other, in such a manner that little or no grinding action is accomplished during the downward movement of the balls.

It has been found by actual tests, that the most efficient grinding action is attained in mills of this kind when the balls are not thrown apart or separated from one another at any period in their upward or downward movement, but remain in rolling and therefore grinding contact with each other, or with the intervening raw material, so as to constantly act to grind and reduce the same.

It has also been found that the most efficient action in mills of this kind is obtained by filling substantially one-half of the cavity of the drum with grinding balls, and rotating the same at such a speed and with such frictional engagement with the peripheral wall, that the balls are carried upward in the rear side of the drum so as to roll downward and forward in grinding contact with each other through the central or axial region of the drum; without being separated from each other, or diverted from or impeded in their most efficient grinding action, by the presence of a baffle wall or a suction tube in the middle or central region of the drum.

It is, therefore, an important purpose of the present improvement to construct and arrange the rotary drum, and the material feeding and withdrawing devices, so as to leave the entire lower and upper rear regions in the drum, including the central or axial region thereof, free of obstructions; so that the drum may be filled substantially half full of grinding balls, and may be operated so that the balls will be carried upward and rearward and will then roll upon themselves downward and forward through the axial region of the drum, for the most efficient grinding action upon the material which is among the balls.

As a part of the present improvement, this important purpose is attained by providing dust collecting means, which may be in the form of a tubular screen, in the upward, forward region of the drum, and mounting the same upon a flat hollow support located in one end of the drum and extending upward from an axial suction tube leading outward through an axial opening in the same end of the drum.

In combination with such dust collecting means, it is preferred to provide material

feeding means for the drum in the form of an inclined chute, for discharging material into the drum through an axial opening in the other end thereof; and the axial openings in the ends of the drum are enlarged so as to form free annular ports around the feed chute and suction exhaust tubes, respectively, for the admission of the air required to permit an effective withdrawal of dust from the interior of the drum through the suction exhaust tube.

Apparatus embodying the present invention is illustrated in the accompanying drawings, forming part hereof, in which—

Figure 1 is a side elevation of the improved apparatus, showing the rotary drum and feed chute in axial section; and

Fig. 2, a cross section elevation of the apparatus, on line 2—2, Fig. 1;

Similar numerals refer to like parts throughout the drawing.

The rotary drum 3 may have on each end a peripheral track band 4 riding upon flanged wheels 5 mounted on shafts 6; and the drum may be rotated by a central, annular girt gear 7, meshing with a pinion 8 mounted on one of the shafts 6, which may be driven from any suitable source of power.

A central opening is provided in each end of the drum, and the same may be formed by the inwardly flared conical collars 9 and 9'; and a downwardly inclined tubular chute 10 is mounted so that its discharge end will protrude into but not through the opening formed by the collar 9, for feeding material into the drum without extending into the same.

A suction exhaust tube 11 is mounted, as on a pedestal 12, at the other end of the tube, so that one end will extend into and through the opening formed by the collar 9'; whence the shape of this tube is changed to a flat hollow supporting arm 13 extending upward and forward within the drum immediately adjacent to the end wall thereof.

On the upper end of the hollow supporting arm 13, is formed a tubular elbow 14 in which is secured one end of a dust collecting receptacle 15, which may be in the form of a slotted screening tube, as shown, and is located in the upper forward region of the drum, so as to leave the remaining regions of the drum free for the unobstructed movements of the grinding balls and the raw material.

The other outer end of the suction exhaust tube 11 may be connected directly within the inlet orifice of an exhaust fan 16, which in turn may be directly connected with a motor 17, for exhausting dust by suction from the upper forward region of the drum and discharging the same through an outlet pipe 18 leading from the fan.

The described construction and arrange-

ment of the apparatus, leaves the middle region of the rotary drum without any impediment for the free movement of the grinding medium through the same.

In the operation of the apparatus, the rotary drum is filled substantially half full of grinding balls, and the drum is rotated at such a speed as will carry the balls upward in the rear side of the drum only far enough as to roll upon each other downward to the forward side through the middle region of the drum, without, however, being thrown away from each other in any of their movements, as shown in Fig. 2 of the drawing.

It has been found that a drum having a diameter of some 4 ft. 6 in. and a ball charge filling substantially half of its cavity, may be rotated at the rate of 28 R. P. M. to accomplish the desired result which has been described.

Raw material is then fed into the drum through the feed chute 10, which may be in the form of small lump, nut or slack coal, until the same fills all the interstices between the grinding balls and in addition thereto may fill something more than one-half of the cavity of the drum; whereupon the grinding action of the balls upon the material and of the material upon itself serves to reduce the same to a fine or impalpable powder, which rises by its own buoyancy into the region of the drum above and forward from the mass of grinding balls and raw material in the lower and rear regions thereof.

The speed of rotation of the drum is so slow that very little if any unground material rises into the upper forward regions of the drum, from which the powdered material is withdrawn from the drum by the operation of the exhaust fan through the suction tube and dust collecting receptacle in the upper forward region of the drum.

The exhausting action of the fan is permitted by the entrance of air into the drum through the annular ports in the ends thereof, to take the place of the air and dust exhausted therefrom; and the induction of air through these ports into the drum also prevents the ejection of much, if any, dust through the same.

The annular port around the exhaust suction tube is preferably formed less in width than the size of the grinding balls, so as to prevent any of the same from passing outward through the same; and when the end of the feed chute 10 is eccentrically positioned in the opening of the collar 9, a shield 19 may be secured to the chute adjacent to the rim of the conical collar for preventing the ejection of grinding balls through the same, which shield may be provided with apertures 19* to permit the flow of air into the drum. Furthermore the in-

wardly flared shape of the conical collars 9 and 9' serves to retain the grinding balls in the drum.

It will be understood that the fineness of 5 the powdered material which is withdrawn from the drum, may be controlled by the speed of the exhaust fan and the resulting rate of the movement of air from the drum through the dust collecting receptacle.

10 I claim:

1. A pulverizing mill including a rotary drum with a central opening in each end thereof, grinding media as balls, filling substantially half the cavity thereof, feed 15 means for delivering raw material into the drum through one end opening thereof, and suction exhaust means including a collecting receptacle extending longitudinally and substantially across the upper region of the 20 drum and a radially extending flat hollow support adjacent the other end of the drum providing communication from the collecting receptacle through the other central end opening for withdrawing dust from the 25 upper region of the drum through the other end opening thereof, there being air inlet ports in the ends around the feed and exhaust means, and the middle region of the drum being without impediment for the free movement of the grinding media there- 30 through.

drum being without impediment for the free movement of the grinding media there- 30 through.

2. A pulverizing mill including a rotary drum with a central opening in each end thereof, grinding media as balls, filling substantially half the cavity thereof, feed means 35 for delivering raw material into the drum through one end opening thereof, and suction exhaust means including a tubular collecting screen extending longitudinally and substantially across the upper region of the 40 drum and a radially extending flat hollow support adjacent the other end of the drum providing communication from the collecting screen through the other central end opening for withdrawing dust from the upper region of the drum through the other end opening thereof, there being air inlet ports in the ends around the feed and exhaust means, and the middle region of the 45 drum being without impediment for the free movement of the grinding media there- 50 through.

In testimony that I claim the above, I have hereunto subscribed my name.

LOUIS C. BONNOT.
